UNITED STATES PATENT OFFICE.

CHARLES W. BRITCHER, OF SPRINGFIELD, MASSACHUSETTS, ASSIGNOR TO THE BAB-COCK PRINTING PRESS MANUFACTURING COMPANY, OF NEW LONDON, CONNECTICUT, A CORPORATION OF CONNECTICUT.

METHOD OF PREPARING CUTTING AND SCORING MATRICES FOR PRINTING PRESSES.

1,416,682.

Specification of Letters Patent. Patented May 23, 1922.

Application filed June 30, 1919. Serial No. 307,810.

To all whom it may concern:

Be it known that I, CHARLES W. BRITCHER, a citizen of the United States, and a resident of Springfield, in the county of Hampden and State of Massachusetts, have invented certain new and useful Methods of Preparing Cutting and Scoring Matrices for Printing Presses, of which the following is a specification.

10 My invention relates to an improved method of preparing scoring and cutting devices for printing presses, more particularly the jacket and matrix with which the cutting and scoring rules cooperate to cut 15 and score heavy paper or cardboard.

The ordinary method at present followed in preparing a printing press for cutting and scoring heavy paper or cardboard from which folding boxes and various articles 20 are made, consists in setting up a form of cutting and scoring rules in a printing chase, suitable furniture and quoins being employed to retain the rules in place in the chase. These rules, it may be stated, are set in the 25 chase on edge, and the cutting rules, i. e., those which are to cut through the cardboard have sharp top edges for cutting, whereas, the scoring rules, which are slightly lower than the cutting rules, have rounded or dull 30 top edges. It is necessary to prepare a matrix for the rules, consisting of a pad, generally of heavy manilla paper, which is secured fast to the cylinder jacket and which is cut or routed out to correspond with the 35 scoring rules to permit the scoring rules to press the stock slightly into the matrix. It has been the custom to prepare this matrix on the cylinder of the printing press. Where the rules are arranged to cut and score a 40 great many small designs on large sheets, as, for instance, where small tack boxes are cut and scored, or where an intricate design is cut and scored, the preparation of the matrix takes considerable time, in some cases 45 the preparation taking several days. Under the former method of preparing the cutting and scoring matrix the printing press must remain idle; that is, it can not be used while the matrix is being prepared. In addition, 50 it is a slow process to rout out the matrix while on the printing press because the various devices on the printing press are more or less in the way of the workers.

The object of my invention is to provide a method of preparing the matrix whereby the above objections may be avoided. Under the present method the printing press may be continued in use (on some other job) while the cutting and scoring matrix is being prepared, so that the press is not necessarily rendered idle while the matrix for a cutting and scoring job is being prepared. Furthermore, the work of actually preparing the matrix is made easier as all parts of it are more accessible for the workers while they are routing out.

In the application of F. S. English, Ser. No. 307,798 there is shown a removable jacket for printing presses, which is very convenient in carrying out my process and I prefer to use that device in my present method though I do not wish to be understood as limiting myself to the use of any particular apparatus.

In the drawing forming part of this application.

Figure 1 is an end elevation and Figure 2 is a front elevation of a dummy cylinder on which the routing of the matrix may be done.

The first step in my new process is to prepare the rules for cutting and scoring for the particular piece of work or job. This is done by selecting or preparing the necessary cutting and scoring rules and furniture and setting up the form in the chase and locking it in the same manner as heretofore. The rules may be straight, curved, of both, and they may be arranged to provide for cutting and scoring any simple or intricate designs and in this respect the preparation of the rules in the chase may follow the present practice. It is understood that the cutting rules have sharp top edges whereas, the scoring rules have dull or rounded top edges and the former project a few thousandths of an inch higher than the latter.

The chase with the rules locked therein is then attached on the bed of a regular printing press on which the job is to be finally run. A removable metal jacket, such as is shown in said application of F. S. English is attached to the cylinder of the printing press preferably in the manner shown in the said application and in such manner that this metal jacket can be re-

5 moved from the press to permit any other jacket or blanket to replace the one removed. The matrix sheet which may be heavy manilla stock, from which the matrix is to be made, is securely attached to the metal jacket preferably by gluing it there-to to secure a close and even contact throughout.

10 The jacket and matrix sheet having been secured to the printing press cylinder in the same position in which they are to be placed when the job is being run off, the next step is to obtain an impression of the rules on the matrix sheet. It may be here stated 15 that the make ready is not prepared until the matrix is finally prepared for use.

However, some make ready may be prepared by padding the jacket in order that the cutting rules will cut through the matrix 20 sheet and stop just at the surface of the jacket. In that case the make ready is glued to the under side of the jacket so that it will be removed with the jacket. It is not necessary to prepare this partial make ready as 25 all the make ready may be prepared when the jacket has been returned to the press.

As above stated, an impression of the rules is now taken. This may be done by inking the form by means of a hand operated inking 30 roller. The cylinder and bed of the printing press are then moved so that an impression of the rules is taken upon the matrix sheet. At some places or at all places the cutting rules may cut through the matrix 35 sheet as far as the metal jacket but if no make ready has thus far been prepared all parts of the cutting rules may not pass entirely through the matrix sheet, but where they do not cut through there will be an 40 ink impression showing the location of the cutting rules. The ink impression will show on the matrix sheet the location and shape of every scoring rule.

45 The jacket and matrix sheet are now removed from the printing press and they are mounted temporarily on a dummy support, such as the device shown in Figures 1 and 2. The chase containing the form may also be removed from the bed of the printing 50 press. Some other form and another jacket or a blanket may be attached to the printing press and the latter may be used to print, or cut and score on some other job while the matrix referred to is being routed 55 on the dummy device. Thus far the time of the press has been taken up only to secure an impression of the scoring and cutting rules on the matrix sheet and this required but a small period of time. From now on and 60 until the scoring and cutting matrix is ready the press may be used for other work. The preparation or routing of this matrix may take hours and even days to prepare, during which time the printing press may be 65 used for other work.

The jacket and matrix sheet are now mounted on the dummy device which latter may be a simple form of support as shown in Figures 1 and 2. This consists of a cylinder 1 about the same size as the cylinder 70 of the printing press, and this is mounted on a shaft 2 supported in uprights 3 of a frame 4. There is a handwheel 5 by means of which the cylinder 1 may be revolved, and there is a lever 6 for locking the cylinder 75 against rotation. The jacket is secured at one end by the clamps 7 and at the other by turnbuckles 8, so that it lies snugly against the periphery of the cylinder 1.

80 The routing out of the matrix sheet is carried on while the jacket and sheet are mounted on the dummy device. The routing will be done along the lines represented by the impression markings on the matrix sheet and the routing may be done with a knife, 85 or wheel, in the manner well known in the art. It may be noted that this routing consists in cutting away or removing part of the matrix sheet along the lines marked by the scoring rules to provide depressions in 90 the matrix. While the matrix is being routed on this dummy device all parts of it are accessible to the workman whereas, in routing on the printing press there is not always sufficient space to allow freedom for 95 the workman.

When the routing has been completed the jacket and matrix are returned to the printing press. If the chase containing the form was removed from the printing press while 100 the routing was being done it will now be returned and mounted on the bed of the press. The jacket and matrix will be secured in place on the printing press cylinder. The pressman will now prepare the make ready. 105 The jacket may be padded locally or the rules themselves may be underlaid and as make ready is well known in the art a detailed description thereof is not here necessary.

110 When the make ready is completed the press will be ready for the scoring and cutting operation.

From the above it will be apparent that instead of the printing press remaining idle 115 while the routing of the matrix is taking place and which sometimes takes a day or more, the press simply remains idle or non-productive for the brief period required to take an impression and to remove and 120 replace the jacket. Furthermore, the workman has more freedom for routing the matrix and if desirable several workmen may work at the same time on the matrix.

125 While I have described my invention as used with a printing press it will be obvious that the same may be employed in connection with a cutting and scoring press or with a printing press wherein the inking mechanism is omitted.

Having described my invention, what scoring matrix for presses, which consists I claim is:

1. The method of preparing a cutting and scoring matrix for presses, which consists of first taking an impression on a press from a form containing cutting and scoring rules, upon a matrix sheet attached to a removable cylinder jacket, removing the jacket and matrix sheet to a separate or dummy support, preparing or routing the matrix sheet while said jacket is removed from the press, afterwards returning said support, preparing or routing the matrix sheet while said jacket is removed from the press, and after returning said jacket and the matrix to the press whereby the latter may be operated for cutting and scoring.

2. The method of preparing a cutting and

scoring matrix for presses, which consists of first taking an impression on a press from a form containing cutting and scoring rules, upon a matrix sheet attached to a removable cylinder jacket, removing the jacket and matrix sheet to a separate or dummy support, preparing or routing the matrix sheet while said jacket is removed from the press, afterwards returning said support, preparing or routing the matrix sheet while said jacket is removed from the press, and after returning said jacket and the matrix to the press whereby the latter may be operated for cutting and scoring.

Signed at Springfield, in the county of Hampden and State of Massachusetts, this 30 22nd day of May, 1919.

CHARLES W. BRITCHER.
